UNITED STATES PATENT OFFICE.

JOHN F. OHMER AND ELMER H. BRIDENBAUGH, OF DAYTON, OHIO, ASSIGNEES TO
OHMER FARE REGISTER COMPANY, OF DAYTON, OHIO.

TICKET ISSUING AND RECORDING MACHINE.

992,380.

Specification of Letters Patent.

Patented May 16, 1911.

Application filed June 16, 1909. Serial No. 502,530.

To all whom it may concern:

Be it known that we, JOHN F. OHMER and ELMER H. BRIDENBAUGH, citizens of the United States, residing at Dayton, in the county of Montgomery and State of Ohio, have invented certain new and useful Improvements in Ticket Issuing and Recording Machines; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in ticket-issuing and recording machines, and embodies certain improvements of the ticket-issuing and recording machine shown and described in Letters Patent No. 892,876, granted to ourselves July 7, 1908.

The object of the present invention is to provide certain means for preventing the operator from operating the machine too quickly, and to thereby prevent any tearing or mutilating of the ticket strip in the operations of the machine.

A further object of the present invention is to provide registering mechanism through the instrumentality of which the total value of all tickets issued may be ascertained, and various other improved features to be hereinafter more fully described.

In the accompanying drawings, Figure 1, is a front elevation of a machine of the above type in which our improvements are utilized. Fig. 2, is an elevation of the left side of the machine as seen in Fig. 1. Fig. 3, is an elevation of the right side of the machine. Fig. 4, is an enlarged side elevation of the counter mechanism for recording the total cash fares. Fig. 5, is a front elevation of the same. Fig. 6, is a detail view of the actuating means of said counter. Fig. 7, is a detail view of the locking device. Fig. 8, is a sectional elevation on the line *b b* of Fig. 1. Fig. 9, is a sectional elevation on the line *a a* of Fig. 1. Fig. 10, is a view of a detached ticket. Fig. 11, is a view of the fare or ticket indicator.

Throughout the specification and drawings, similar reference characters indicate corresponding parts.

Mounted in parallel frame plates 1 and 2, is a shaft 3 upon which is supported a large feed roll 4, above which a pressure roll 5 is mounted upon a swinging frame 6. The pressure exerted by this feed roll 5 upon the ticket strip, is regulated by a thumb screw 7. Between the larger feed roll 4 and the smaller pressure roll 5, the ticket strip 8 passes, as it is unwound from a large roll 9 which is housed within the lower portion of the machine. The ticket strip passes upwardly at the back of the machine through guide plates 10 and 11 and thence through upper horizontal side plates 10' and 11' in which there are suitable openings which expose the ticket strip to the action of the rollers 4 and 5. The plates 10 and 10' support shiftable punches 12 which are similar to the punches shown and described in our prior Letters Patent hereinbefore referred to. The said punches are set by finger knobs 13 through link connections 13', and their purposes are to punch and indicate on the tickets the dates, the time of issuance, the stations or points to which the tickets are issued, the fare or traffic value and any other desirable matter.

Upon the shaft 3 and on the outside of the frame plate 1, is mounted a pinion 14 which engages a large gear 15 mounted on a shaft 16 having suitable bearings in the frame plate 1 and 2. Also on shaft 16 is mounted a mutilated gear 17 which is actuated from a segment gear 18 on a pivot 19 to intermittently rotate said gear 17. Also mounted on the pivot 19 and rotating concurrently with a gear 18, is a gear 20 that meshes with a gear 21 on a pivot 22. The gear 18 is also mounted on the pivot 19. The gear 21 in turn, meshes with a gear 23 on a pivot 24. The ratio of the train of gearing consisting of gears 23, 21 and 20, is such that two revolutions of the gear 23 will drive the gear 20 one revolution. Also mounted upon the pivot 24 in addition to the gear 23, is a locking disk 26, a detail of which is shown in Fig. 7, a ratchet 27 and a crank 28, by means of which the machine is operated. Owing to the ratio of the gears 23, 21 and 20, the crank 28 will have a higher rate of speed than the feed roll 4. The larger feed roll 4 before referred to is provided with suitable peripheral serrations 42 which engage the ticket strip 8 to effectually feed the same.

The operating handle 28 being of short radius and owing to the ratio of the gearing, a sufficient speed cannot be secured during its manual operation, to drive the feed roll 4 with enough force to tear the ticket strip by the serrations 42. The ratchet 27 is engaged by a spring-controlled pawl 29 and prevents a retrograde movement of the operating handle 28. The above-described mechanism including the various gears referred to, is the actuating mechanism of the machine, and such mechanism is locked in a normal position by a spring-controlled pawl 30 engaging a notch 30' in the disk 31, the latter being attached to the gears 18 and 20. The disk 31 carries a pin 32 which is part of the punch-actuating device. The punches are actuated by levers 33 having arms 34 which are connected by links 35. The arm 34 of a vertical series of punchers is provided with a pin 36 engaged by a sliding member 37 supported at 38 to the plate 1. The member 37 carries a finger 39 engaged by the pin 32 on disk 31 during the rotation 25 of said disk. The forward lever 33 of the horizontal series of punches has an arm 40 which is connected with the pin 36 by means of a link 41, and by means of which the vertical and horizontal series of punches 30 operate concurrently as in our prior patent.

Mounted in the plates 2 and 43 is a shaft 44 having counters 45 thereon, one for each fare to be registered. These counters carry star wheels 46 which are engaged by an actuator 47 when any one of said counters is properly set. The actuator 47 is driven from a gear 48 on the shaft 16 before referred to. The counters 45 are rotated in setting them, by a thumb piece 49 on a shaft 50 journaled in the plates 1 and 2. The shaft 50 carries a gear 51 which meshes with an idler gear 52 which in turn, meshes with a large gear 53 on the shaft 44.

The means for ascertaining when a counter is in a position to be actuated is as follows: One the outer end of the shaft 44 a cam 54 is placed which actuates a slide 55 by means of a pin 56. The upper end of the slide 55 engages one arm of a bell crank lever 57 pivoted at 58. The upper arm of said bell crank lever engages an indicator 59 that extends on the outer side of the casing and operates in connection with a plate 60 having indicated thereon the different fares to be registered, see Fig. 11. These features are the same as in our prior patent.

When the pointer or indicator 59 is moved opposite any specific fare denomination, the counter 45 corresponding to that fare is placed in operative relation with the actuator 47. It will be borne in mind that the counters 45 are detail counters, or in other words, they register the number of different fare denominations and do not register the total cash value of the fares. A counter 61

which is actuated from the gear 48, through a pinion 62, registers the number of tickets issued, see Fig. 1. Means are provided for preventing the machine being operated while the counters 45 are being set, or vice versa, comprising a dial 63 mounted on shaft 44 and having notches 64 which are engaged by the lower end of the spring-controlled pawl 64, which, together with the dial 63, maintain the counters 45 in a locked position when set. A projection 65 on the pawl 64 engages a lever 66 pivoted at 67 to the plate 43, see Fig. 1. The left end of this lever 66 engages a slide 68 mounted on the plate 1 and supported by a pivot 24 and a screw 69. This slide 68 at its lower end has a projection 70 which lies below a notch 71 in the locking disk 26 before referred to, and when the counters 45 are being set, the pawl 64 rides out of the notches 64 causing the lever 66 to rock, and the slide 68 to elevate and carry the projection 70 into the notch 71 of the disk 26 and thus prevents the machine from being actuated by turning the crank 28. If the crank 28 is being turned, the projection 70 cannot enter the notch 71, and as a consequence, the pawl 64 is locked in one of the notches 64 of the wheel 63, and thus the counters 45 are prevented from being set.

A total cash counter is provided for registering the total money value of all the tickets irrespective of their individual values. This counter consists of three denominations of wheels, to wit: Hundreds, thousands, and tens of thousands and are indicated by 77, and a unit and tens wheel indicated by 78. These cash counters are mounted upon a shaft 76 which in turn, is mounted in a frame 75 supported on plate 43, see Figs. 4, 5 and 6. Suitable transfer mechanism 79 of any of the well-known types, is provided between the various counting wheels 77 and 78, and the unit and tens wheel is provided with a ratchet 79 engaged by a pawl 80 pivoted at 83 to a gear 71. A retaining pawl 82 is provided to prevent any retrograde movement of said unit and tens wheel 78, see Fig. 3.

The gear 71 meshes with a gear 84 on a shaft 85, the latter gear carrying a plate 86 having shoulders 87 adapted to engage the upper end of a lever 88 to set the counter to register the different fare values; the lever 88 is pivoted at 89 to the frame 75 and has an extended arm 90 which engages a pin 91 on the slide 55 hereinbefore referred to in connection with the fare indicator 59. The position of the lever 88 is therefore, controlled by the slide 55 and the position of the slide is controlled by the indicator 59. If the indicator stands at the fare indication of 5¢ as it does in Fig. 11, the upper end of the lever 88 will be in a position to engage the lower shoulder 87 of the plate 86 which corresponds to the

fare denomination of 5 ¢, see Fig. 4. The plate 86 and the gear 84 are rigidly secured to the shaft 85 and are under the control of the spring 91^b which is mounted 5 upon said shaft. When the plate 86 is released, by means hereinafter described, the spring 91^b will rotate the gears 71 and 84 a distance corresponding to the fare indicated. During this operation, the pawl 80 10 will ride over the ratchet 79 and will be in a position to rotate the unit and tens wheel 78 a sufficient distance to register the value of the fare indicated. See Fig. 6. On the back of the gear 84 is a lug 91^a shown in 15 dotted lines in Fig. 6, which is engaged by a pin 92 on a link 93 carried by a crank 94 on a sleeve 96; the sleeve 96 carries a gear 97 which receives movement from the large feed roll 4 through gear 98, shaft 20 99, gear 100 and gear 101 on the feed roll shaft 3. One revolution of the feed roll 4 imparts one revolution to the gear 97. The pin 92 extends through the link 93 and rides in a cam race 102 which is in the face 25 of a stationary cam 95 on shaft 85.

A depressed portion 104 is provided in the cam 95 and when the crank 94 is initially rotated, the pin 92 will ride into said depressed portion of the cam race and release 30 the projection 91^a, thus allowing the gears 84 and 71 and pawl 80 to revolve under the influence of the spring 91^b, thereby placing the counter in a set position. In this set position, the projection 91^a lies along the 35 circumferential portion of the cam race 102 and said projection will be engaged by the pin 92 during its extended movement and carried back to the normal position shown in Fig. 6, thereby registering the fare indicated 40 on the unit and tens wheel 78. An arm 105 is attached to the crank 94 and engages the top of the pawl 80 when said pawl is in its normal position. This prevents the counter 78 from being rotated when the 45 parts are in their normal position. By the term "set position" used in connection with the total cash count, it will be understood, is meant the position of said counter to register each fare or ticket value as indicated 50 by the shoulders on the plate 86 and the position of the pointer 59, Fig. 11.

The operation of the machine is as follows: When the operator desires to issue a ticket of a given denomination or value, the thumb-piece 49, Fig. 1, is rotated until the desired fare is indicated on the tablet 55 by the pointer 59, see Fig. 11; this places the detail counter 45 corresponding to that fare opposite the actuator 47. The upper 60 end of the lever 88 will also be set in a position corresponding to the value of the fare indicated, movement being imparted to said lever 88 from the slide 55, the latter being moved by the lever 57 in shifting the indicator 65 59.

The various punches 12 are set by means of the finger pieces 13 and the crank 28 is then rotated. During the first revolution of said crank, the punches are actuated to punch the tickets at the various points as 70 indicated in Fig. 10, and during the second revolution of said crank the feed roll 4 is rotated and the ticket is fed from the machine. During the rotation of the feed roll 4, the plate 86 has been released by the pin 75 92 which places the total cash counter in a set position. The continued movement of the feed roll carries the pin 92 into the cam race 102 where it picks up the lug 91^a and carries it back to its normal position, thereby 80 actuating the total cash value wheels 77 and 78 through the ratchet 79 and pawl 80.

Having described our invention we claim:

1. In a machine of the type specified, the combination with a feed roll adapted to feed 85 a strip of tickets having various cash values printed thereon, means for indicating the cash value on said tickets, and means for actuating the feed roll, of a counter adapted to register the total cash values of said 90 tickets, setting mechanism adapted to arrest said counter at different points of its movement in registering different ticket values, mechanism for actuating said counter to the extent of the movement permitted by the setting mechanism, said actuating mechanism being operated from the feed roll during 95 each continuous rotation of said feed roll in feeding each ticket from the machine.

2. In a machine of the type specified, the combination with a feed roll adapted to feed 100 tickets having various cash values printed thereon, a punch adapted to indicate the selected cash fare on each ticket, and means for actuating said feed roll, of a counter 105 adapted to register the total cash values as indicated by said punch, means for allowing said counter to be placed in a position to register the different ticket values, and means for actuating said counter, said counter-actuating means being operated from the feed roll during each continuous rotation of 110 said feed roll in feeding each ticket.

3. In a machine of the type specified, the combination of a cam, a sliding member actuated thereby, an indicating lever and a 115 setting lever actuated by said slide, and a counter upon which the total money values of tickets are registered, and means interposed between the setting lever and said 120 counter for placing the counter in a position to register the fare indicated by the indicating lever.

4. In a machine of the type specified, an actuating slide and means for operating the 125 same, in combination with an indicating lever and a setting lever actuated by said slide, and a counter for counting the total values of the tickets, the operation of said counter being controlled by the setting lever. 130

5. In a machine of the type specified, a feed roll adapted to feed a strip of tickets, a series of punches to perforate said tickets, means having a continuous rotary motion for operating the punches and the feed roll consecutively.
6. In a machine of the type specified, a feed roll adapted to feed a strip of tickets, a series of punches adapted to perforate said tickets prior to their feed, a sliding member, mechanism engaged thereby for operating the punches, a dial actuating said sliding member, a crank, a train of gearing between said crank and said dial, and an intermittently-rotating train of gearing between said crank and the feed roll whereby said feed roll is enabled to impart a gradual initial feed to the ticket.
7. In a machine of the type specified, a feed roll having peripheral serrations adapted to engage a ticket strip to feed the same upon the rotation of said roll, and a stamp adapted to indicate the cash value of each ticket, in combination with a crank having a higher rate of speed than the feed roll, and a train of gearing interposed between said crank and said feed roll for imparting an intermittent movement to said feed roll and for actuating said feed roll and stamp consecutively.
8. In a machine of the type specified, a feed roll adapted to feed a ticket strip having printed thereon a multiplicity of fare values, a punch adapted to indicate on said ticket its fare value, a crank adapted to rotate said feed roll, a dial on said crank, a multiplicity of counters one for each fare value, a shaft around which said counters revolve as a unit, a disk mounted on said shaft, and means interposed between the disk and the dial whereby, when one is being actuated the other is locked.
9. In a machine of the type specified, a feed roll adapted to feed a ticket strip having printed thereon a multiplicity of fare values, a punch adapted to indicate on said ticket its fare value, a crank adapted to rotate said feed roll, a disk 26 on said crank, a multiplicity of counters one for each fare value, a shaft around which said counters revolve as a unit, a dial 63 mounted on said shaft, a sliding member 68 adapted to engage and lock said disk 26, a lever 66 adapted to actuate said sliding member, a lever 64 adapted to lock said dial 63 and to actuate the lever 66, whereby when the dial 63 is locked, the disk 26 is free, and when said disk is locked, the dial is free.
10. In a machine of the type specified, a feed roll, and means for actuating the same, in combination with an indicator adapted to indicate fare values, a setting lever moving concurrently with said indicator, a counting wheel, rotatable setting means adapted to engage said lever and to actuate said count-
- ing wheel, and an actuator operated from said feed roll and adapted to release said rotatable setting means during its initial movement and to return said setting means to a normal position during the continued movement of said actuator.
11. In a machine of the type specified, the combination with a feed roll, means for actuating said feed roll, and an indicator, of a setting lever operated concurrently with said indicator, a counting wheel, a spring-controlled notched plate adapted to be released and to engage said setting lever, means actuated from said feed roll adapted to release said notched plate and to return the same to a normal position, and connecting mechanism between said counting wheel and said plate, whereby said counting wheel is actuated during the return movement of said plate.
12. In a machine of the type specified, feed roll, means for actuating said feed roll, an indicator, a setting lever operating concurrently with said indicator, a counting wheel, mechanism adapted to engage said setting lever during the forward movement of said mechanism and to actuate said counting wheel during its rearward movement, a spring controlling said mechanism during its forward movement, and means operated from said feed roll and adapted to place said mechanism under the control of said spring during the initial movement of said means and during the continued movement of said means to return said mechanism to its normal position and thereby actuate the counting wheel.
13. In a machine of the type specified, the combination with a feed roll, means for actuating said feed roll, and an indicator, of a setting lever operated concurrently with said indicator, a counting wheel, a plate having notches therein corresponding in position to the fare values on the indicator, a spring controlling said plate during the forward movement of said plate, a gear and ratchet connection moving concurrently with said plate and adapted to actuate said counting wheel, a stationary cam, a pin in operative relation with said cam and actuated from the feed roll, said pin being adapted to release said plate to permit the spring to actuate the same, and to return said plate to a normal position after the spring has actuated it.
14. In a machine of the type specified, a counting wheel, a ratchet on said counting wheel, a pawl engaging said ratchet, a gear upon which said pawl is mounted, a second gear having a projection thereon and in mesh with said first named gear, a notched plate attached to said second gear, a setting lever, a spring adapted to move said plate in engagement with said lever, and means for placing said lever in a position to be en-

gaged by the various notches on said plate and whereby the movement imparted to the counting wheel is varied.

15. In a machine of the type specified, an indicator adapted to indicate fare values, a setting lever moving concurrently therewith, a counting wheel, rotatable setting devices adapted to engage said lever and to actuate said counting wheel, an actuator adapted to release said rotatable setting devices during its initial movement and to return said setting devices to a normal position during the continued movement of said actuator, and means for operating said actuator.

16. The combination with a feed roll adapted to feed tickets having various cash values indicated thereon by perforations, a punch adapted to perforate said tickets according to their fare values, and means for actuating said feed roll, of a plurality of detail counters, one for each cash value, of a total counter adapted to register the total cash values of said tickets, and means for concurrently actuating one of the detail counters and the total cash counter.

17. The combination with a feed roll adapted to feed tickets having various cash values indicated thereon by perforations, a punch adapted to indicate on said tickets the fare values, and means for actuating said feed roll, of a plurality of detail counters, one for each cash value, of a total counter adapted to register the total cash value of said tickets, means for setting any one of the detail counters and the total cash counter to registering positions, and means for actuating said counters after being set.

18. The combination with a feed roll adapted to feed tickets having various cash values indicated thereon by perforations, a punch adapted to indicate on said tickets their fare values, and means for actuating said feed roll, of a plurality of detail counters, one for each cash value, of a total counter adapted to register the total cash value of said tickets, means for setting any one of the detail counters and the total cash counter to registering positions, and means for actuating said counters after being set, said setting means and said actuating means being operated during each continuous rotation of said feed roll in feeding each ticket from the machine.

19. The combination with a feed roll adapted to feed tickets having various cash values indicated thereon by perforations, a punch adapted to indicate on said tickets their fare values, and means for actuating said feed roll, of a plurality of detail

counters, one for each cash value, of a total consecutive counter adapted to register one number each time any one of the detail counters are actuated, and means for simultaneously actuating one of the detail counters and the total consecutive counter.

20. The combination with a feed roll adapted to feed tickets having various cash values indicated thereon, a punch adapted to indicate on each ticket the value thereof, devices for actuating said feed roll, and a series of detail counters one for each cash value, of a counter adapted to register the total cash value as indicated by the punch, stop mechanism for said total cash counter, means for setting one of the detail counters and the total cash counter stop mechanism concurrently, and means for actuating said counters, said last named means being operated from the feed roll actuating devices during each continuous rotation of said feed roll in feeding each ticket.

21. The combination with a cam, an indicator, setting devices, means connecting said cam, indicator and setting devices, of a counter upon which total money values are registered, means having a setting movement in one direction, and an actuating movement in the other direction, interposed between the setting devices and the counter for allowing the counter to register a value corresponding to the value shown by the indicator, and means for actuating said counter.

22. The combination with an actuating slide, an indicator, and a setting device actuated by said slide, of a counter for counting the total value of tickets, the operation of said counter being controlled by the setting device, and means having a setting movement in one direction, and an actuating movement in the other direction for allowing said counter to be actuated to an extent predetermined by said indicator.

23. The combination of a feed roll adapted to feed a strip of tickets, a series of punches to perforate said tickets, a series of indicators to indicate the positions of the punches, means for simultaneously setting the punches and indicators, and means having a continuous rotary motion for operating the punches and the feed roll consecutively.

In testimony whereof we affix our signatures, in presence of two witnesses.
